HANDLE FOR MATTRESSES, CUSHIONS, AND
THE LIKE

Michael Bechik, St. Paul, Minn.

Application May 10, 1934, Serial No. 724,880

5 Claims. (Cl. 5—345)

This invention relates to a handle means for mattresses of different characters where it is desired to provide a hand engagement so that the mattress or the like can be readily lifted or turned by engagement with the handle. I have disclosed certain outstanding features of my handle in my Patent 2,011,747 dated August 20, 1935, wherein I have pointed out that it is desirable to provide a handle which lies flat against the side wall or boxing of the mattress or cushion and is of an inconspicuous character. This structure provided a handle which was strong and durable, capable of carrying the load of the mattress without tearing or breaking the side wall, and permitting the side wall to flex inward but to normally remain flat and stretched smooth between the ends of the handle when the handle was not engaged.

It is a feature of this handle to provide a simple, inexpensive means for anchoring the ends of the flexible handle member to the metal inner anchoring bar which is placed along the inside wall of the mattress or cushion. I provide a clip means formed in the anchoring bar itself which may readily be bent over on the ends of the flexible handle, pinching the same to anchor the ends to the metal reinforcing bar, thus not requiring any other means of anchoring the flexible handle to the bar.

Here I have provided a structure in the metal reinforcing bar for my handle of a very desirable character which includes a thin strip-like metal member having reinforcing rib means extending longitudinally in the same to stiffen the anchoring strip. Thus I am able to use a light-weight metal anchoring member which is strong and durable to hold the ends of the flexible handles spaced apart and which may be readily anchored in the mattress to be associated with the wall thereof.

Further, it is a feature of my handle means to provide connecting means extending from one handle anchoring means to another so as to distribute the load carried by any one of the handles to any one or two of the handles from one to the other, and thereby relieve the strain which would otherwise be centered at the point of anchoring of the member which holds the ends of the flexible handle. With an offset central portion formed in my metal anchoring bar, I provide not only a recess into which the side wall of the mattress may easily flex when the hand engages the handle member to lift the mattress, but also provide an offset for connecting one handle to another to distribute the load, or for

connecting this offset portion of any one of the handles to the inner structure of the mattress or cushion so as to relieve the lifting strain from the points at the end of the handle.

It is a feature of my handle to provide ventilating openings at the ends of the anchoring member so that the anchoring member may act as a support for the ventilators, holding the same in line with the ends of the handle and anchoring member and simplifying the construction of the ventilators which are associated with the handle.

While the features of my handle and its anchoring means may be apparent to some extent from the foregoing, the detail structure and other advantages and features will be more fully set forth.

In the drawings forming part of this specification:

Figure 1 is a perspective view of a portion of a mattress, showing my handle attached thereto.

Figure 2 is a sectional detail showing the manner in which the anchoring member of the handle may be fixed to the inner portion of the mattress or cushion.

Figure 3 is an enlarged section longitudinally through my handle.

Figure 4 is a plan view of the metal anchoring bar used in a form of my handle.

Figure 5 is an end view of Figure 4.

Figure 6 is a section on the line 6—6 of Figure 4.

Figure 7 is a plan sectional detail of a form of my handle and anchoring means therefor.

Figure 8 is a transverse section through a mattress, showing the anchoring means extending from one handle to the other.

Figure 9 is a sectional detail of another form of my handle.

Figure 10 illustrates a plan view of the anchoring bar of my handle of the construction shown in Figure 9.

The drawings illustrate my handle A which is formed with a flexible handle cord 10 adapted to extend along the outside of the wall 11 of the mattress B.

The ends of the handle cord 10 are adapted to be directly anchored to the inner metal reinforcing anchoring bar 12 by the clips 13. The clips 13 are formed by cutting the bar 12 at 14 and bending up a pair of ears 15 into a virtually U-shape, as illustrated in Figure 5, at the time that the bar 12 is formed. The ears 15 of the clips 13 are bent down against the ends 10' of

the flexible cord 10 to pinch and secure the ends of the cord to the ends of the bar 12.

The bar 12 is adapted to be formed with a central offset portion 16 through which the reinforcing rib 17 is formed longitudinally so as to reinforce the bar 12 from end to end. In forming the bar 12 of the handle A with the longitudinal reinforcing rib means 17, it is possible to use a light-weight metal bar for the portion 12 which may be ribbed at the same time that it is bent with the offset central portion 16. The ends of the bar 12 are formed with flat washer-like portions 18 with the opening 19.

The bar 12 is adapted to be secured to the padded mattress wall 11 by means of grommets 20 which anchor the flat washer-like portions 18 to the inner wall of the mattress. The washer-like ends 18 form a broad, flat bearing against the mattress wall material so as to firmly secure the same to the mattress wall and to reinforce the same against the strain placed on it by engaging the handle 10. The offset portion 16 of the bar 12 permits the wall 11 to flex inwardly as illustrated in dotted outline in Figure 3, when the cord 10 is engaged, making a hand hole recess. The moment the hand disengages the cord 10 the mattress wall which is stretched between the ends of the anchoring bar 12, automatically straightens out flat against the inner side of the handle 10. Thus the handle 10 lies flat and virtually inconspicuous when of the same color as the side wall 11, against the same.

In securing my handle A to the side wall of a mattress, cushion or the like, if the same is not padded, a piece of padding material may be laid along the inner surface thereof before the ends of the bar 12 are secured by the grommets 20. This will provide a soft reinforcement between the ends of the handle and will add a stiffness to the side wall at the point of attachment of the handle so that the wall will normally lie flat under the handle 10.

The clips 13 extend from the ends of the washer-like portions 18 and provide additional bearing means for the washer-like ends 18 in engaging against the inner wall of the mattress B in attaching the handle A thereto.

In certain structures of mattresses and cushions it is desirable to provide a connection from one handle A to the other, such as I have illustrated in Figures 7 and 8. In the construction illustrated in Figure 7, the handles A are connected by a strip 22 which extends through the mattress B. The strip 22 may be buttoned at 23 so that the ends of the strip 22 are looped through the offset portion 16 of the member 12. This provides a connection between the handles A so as to distribute the load from one handle to the other and relieves any heavy strain on the side wall 11. In mattresses where the side wall is of real light material and little or no padding is used in the same, the connecting strip 22 is a material advantage in distributing the strain from mattress handles.

A cable 24 may be used in place of the strip 22 which is looped through the offset portions 16 as illustrated in Figure 8 so as to connect the handles A from the offset sides of the mattress B. The offset portion 16 not only forms a recess for the wall 11 to flex into, but provides a very desirable anchoring portion for either the strip 22 or a cable 24 as well as the securing loop 25 illustrated in Figure 2.

In the construction illustrated in Figure 2, the handle A is shown attached to a box spring

which is built up on a slatted frame base C. In this construction the loop 25 is passed through the offset portion 16 of the bar 12 and the ends of the same are attached at 26 to the base frame C of the spring. Thus I provide a means of distributing the load from the offset portion 16 of the handle A in this structure direct to the frame, instead of using a strip or cable connecting to another handle.

It is also desirable in my handle to provide for certain forms thereof a ventilating washer opening 27 illustrated in Figures 9 and 10 which is formed integral with the ends of the bar 12. This washer end 26 forms an additional bearing for the bar 12 in anchoring the same to the mattress wall 11. In this construction the grommet 27 carries a screen 28. This grommet 27 is passed through the opening in the mattress wall and through the opening 29 of the washer-like end 26 and turned over at 30 so as to anchor the ventilator screen 28 directly to the end of the bar 12. In this manner I provide a very simple and desirable ventilating end to the handle A. The clip portion 13 with the ears 15 extends as a shank between the washer ends 18 and the washer ends 26.

These features provide a light-weight bar 12 which is reinforced and of a simple character. The clip 13 positively secures the ends of the handle cord 10 so that the ends thereof are anchored rigidly and against slipping. My handle A is formed virtually of two parts, namely, the handle cord 10 and the light reinforcing bar 12.

In accordance with the patent statutes I have set forth the principal features and details of my handle and I desire to have the same considered within the scope of the following claims with such variations as will be apparent to those skilled in the art.

I claim:

1. A handle assembly for mattresses and the like, comprising a handle member having ends thereon, an anchoring member inside the mattress wall having openings therein through which said ends of said handle member extend, and means formed on the ends of said anchoring member pinched upon the ends of said handle member to fix the ends of said handle member to said anchoring member and grommets also extending through said openings and the mattress wall securing said anchoring member thereto.

2. A handle for a mattress and the like, a hand engaging member, means for anchoring the ends of said member within the wall of the mattress, a flexing space in said anchoring means, and means entirely within said mattress adjacent said flexing space for attaching said anchoring means to the inner structure of the mattress at a point spaced from said wall to distribute the load carried by the hand engaging member.

3. A handle assembly for mattresses and the like in combination with a mattress wall including a flexible handle member having ends thereon, an anchoring member inside the mattress wall formed of thin ribbon-like material having a longitudinal reinforcing rib extending through the larger portion thereof, said anchoring member having openings formed therethrough adjacent the ends thereof, grommets extending through the mattress wall and through said openings securing said anchoring member to the inside of the mattress wall, the flexible handle member overlying the outside surface of the wall and said ends extending through said grommets, and means formed on the ends of said anchoring member pinched over the ends

of said flexible handle member securing the same to said anchoring member.

4. A handle for a mattress and the like in combination with a mattress wall, including a flexible hand engaging member extending along the outside wall of the mattress, a ribbon-like anchoring member overlying the inner surface of the mattress wall, a flexing space in said anchoring member between the ends thereof, a longitudinal reinforcing rib extending through the said flexing space to reinforce said anchoring member, grommet means extending through said wall and through each end of said anchoring member securing said wall and member together, ends on said flexible hand engaging member extending through said grommet means, and means formed integral with the ends of said anchoring

member securing the ends of said flexible handle within the mattress wall to said anchoring member.

5. A handle assembly for mattresses and the like in combination with a mattress wall comprising a handle member overlying the outside of said mattress wall and having ends thereupon, an anchoring member inside the mattress wall having openings therein, grommets extending through said openings and through the mattress wall securing said anchoring member to said wall, said handle ends extending through said grommets, and means attached to the ends of said anchoring member pinched upon the ends of said handle member securing the ends of said handle member to said anchoring member.

MICHAEL BECHIK.
